Primary Examiner — Cynthia Ramirez*Assistant Examiner* — Gino Colan(74) *Attorney, Agent, or Firm* — Martine Penilla Group, LLP(57) **CLAIM**

The ornamental design for an expansion valve, as shown and described.

DESCRIPTION

FIG. 1 is a front view of an expansion valve showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a front perspective view thereof; and,

FIG. 8 is a rear perspective view thereof.

The broken lines are for the purpose of illustrating portions of the expansion valve and form no part of the claimed design.
